PICKUP TOOL

Sverre Idland, Hazel Run, Minn.

Application April 26, 1940, Serial No. 331,791

8 Claims. (Cl. 294—104)

My invention relates to pickup tools and more particularly to the kind used in concrete forms for the removal of the spacer elements between the side walls of the concrete molding form.

5 My invention further provides a tool of length and width sufficient to enable the operator to dislodge the spacer elements from their positions between the side walls of the concrete forms during the pouring of the concrete and then pick up the same.

10 Another object of the invention is to provide a tool which will readily facilitate the dislodgment of the spacer elements by either bumper or grabbling means or by picking up the same after 15 they have become dislodged.

Another object of the invention resides in the provision of a tool of this class that can be economically produced and which may be readily handled efficiently for the picking up of debris 20 in the bottom of forms such as leaves, shavings, paper, etc.

With these and other objects the invention will become apparent from references to the following description of an embodiment thereof and in 25 which description reference will be had to the accompanying drawing forming part of the specification. Referring to the drawing;

Figure 1 is an isometric perspective of the pickup tool.

30 Figure 2 is a side elevation of the tool's jaws picking up paper debris.

Figure 3 is a side elevation of a spacer element being grappled for dislodgment and removal from 35 its position between the walls of the concrete form.

Figure 4 is a front view of the pickup tool.

Figure 5 is a side view of Figure 4.

Referring to the drawing A represents a handle to which the pickup tool B is secured by fastening means C. The pickup tool B is provided with a face plate 1 whose sides are bent up to form bumper member legs 2 which are connected by impact striker 3. The pickup tool B is provided with side brackets D which sustain a pivot support E to which is secured the movable jaw F. The movable jaw F is at its inner end formed with a loop connection 4 while the outer end is provided with a bite plate 5.

Positioned in the sides of the jaw F is a roller support 6 which sustains the roller 7. At a predetermined point along the length of the pickup tool is a rockable clevis G whose side arms G' are rockably secured to the pickup tool B by the holding means 8. Upon the face of the pickup tool B there is positioned a U shaped spring se-

cured to the face plate 1 and held securely by the fastening means 9. The U shaped spring's free leaf 10, resting well under the jaw supporting member E, permits its free spring end 11 to contact the roller 7, and throw the jaw F into closing 5 position as indicated by the arrow in Figure 5.

The clevis G will hold the loop connection 4 of the jaw F in locked position when the clevis top 12 is projected over the loop member 4 of 10 the jaw and thereby hold the jaw F arrested until released. The clevis G is further provided with a rotatable control member 13 to which is secured a plunger 14 extending through the impact striker 3 to a sensitive control end 15. Along 15 the length of the plunger 14, there is provided a bracket 16 extending up from the plunger 14 to a strut rod 17 secured to the plunger 14 at a point closer to the clevis control member 13. The bite plate member 5 is provided with an edge 18 20 which will cooperate in gripping with the bite edge 19 of the impact striker 3.

In operation, assuming the user was operating the pickup tool within a concrete form to pick up debris prior to the casting of the concrete; 25 he would lower the tool into the form, and assuming that the debris was paper, the tool jaws would be set as in Figure 1 and Figure 5 with a plunger 15 extending through the impact striker so that the edges 18 and 19 would rest over the 30 debris to be picked up. A slight pressure downward upon the tool pole would force the plunger 14 inward, rotating the clevis G about its fastening means 8, so as to free the loop 4 from its holding from under the top member 12 of the 35 clevis G. The release would free the compression forces of the spring S held atop the member 1 so that the spring's free end 11 would exert its force upon roller 7 held rotatable upon a shaft 6 positioned between the jaw sides F and 40 45 force the jaw F outward at the locking end as indicated by arrow in Figure 5.

The jaw F being rockable upon the shaft E would close the space between the jaw edges 18 and 19 and pick up the debris as is best illustrated in Figure 2. By the lifting of the tool from within the form and the opening of the jaw on the outside of the form, the debris may be released. Should it be desired to use the tool as a ram for the removal of spacers, the same 50 can be left in an open position and used as a ram rod using the impact striker edge 3 and the member 5 as bumper edges. Or by the resetting of the tool as shown in Figure 1 and Figure 5, the tool can be used for direct grabbling of the 55

spacers within the form by straddling the spacer so that the top end of the spacer will contact the bracket 16. Any downward pressure upon the handle will tend to push the plunger bracket 5 16 and its associated 14 inward so as to rotate the clevis G upon its fastening 8 and release the loop member 4 of the jaw F which will in turn clamp the spacer tightly within the pickup tool for removal.

10 I claim:

1. A pickup tool for removing the side wall spacer elements from a concrete molding form, comprising a U shaped metallic head having an impact striking surface to disengage side wall spacer elements, impact head holding means, a gripping jaw member pivotally supported by said holding means, a spring supported by said holding means in engagement with said jaw member, a rockable locking means for said jaw member, 20 and a plunger rod extending through said impact striking surface and operative to release said locking means from the gripping jaw member.

2. A pickup tool for removing side wall spacer elements from a concrete molding form, comprising a jaw head having an impact striking surface to disengage side wall spacer elements, holding means for said jaw head, a jaw member pivotally supported by said head holding means in opposition to said impact head, rockable locking and releasing means for said pivoted jaw member, a spring supported by said holding means and in tension against said pivoted jaw member, and a slidable plunger rod extending through the impact head and operable to release said locking and releasing means from said pivotally supported jaw for the purpose set forth.

3. A pickup tool for removing side wall spacer elements from a concrete molding form, comprising a U shaped metallic head having an impact striking surface to disengage spacer elements, holding means for said metallic head, a jaw member pivotally supported by said holding means to cooperate with said metallic head, a spring tensioned against said pivoted jaw member, locking means engaging with said pivoted jaw member and holding the jaw from said im-

pact striking surface head, and a plunger rod to release said locking means for the purpose set forth.

4. A pickup tool of the class described comprising a base, a fixed jaw member carried by said base and having an impact striking surface, a spring tensioned jaw member pivotally supported by said base, locking means normally holding said pivoted member turned on its pivot away from said impact striking surface, and impact 10 actuated means for releasing said locking means from said pivoted member.

5. A pickup tool of the class described comprising a fixed jaw member formed with an impact surface, a jaw member pivotally supported in 15 opposition to said fixed jaw member, a spring means to turn said pivotal jaw member toward the fixed jaw member, a rockable bracket normally engaging with said pivotal jaw member, and holding said member turned away from the 20 fixed jaw, and a control rod extending through the impact head of said fixed jaw member actuatable to release said bracket from said jaw member.

6. The combination as set forth in claim 5, and 25 having a bracket carried by said rod and constituting an impact receiving extension of said rod.

7. A pickup tool of the class described comprising a fixed jaw member, a relatively movable jaw 30 member pivotally supported intermediate its end upon said fixed jaw member, a rockable bracket normally engaging with said movable member to hold the jaw ends of said members separated, and an impact member connected with said 35 means and operable to release said means for the purpose set forth.

8. The combination as set forth in claim 7, and having spring means supported by said fixed jaw member and operable to turn said pivotal jaw 40 member upon its pivot into engagement with said fixed jaw member upon the release of said bracket from engagement with the movable jaw member.

SVERRE IDLAND. 45
